UNITED STATES PATENT OFFICE

JASON C. STEARNS, OF WORCESTER, MASSACHUSETTS.

ELECTRICAL CONNECTING-SOCKET.

1,165,553.

Specification of Letters Patent. Patented Dec. 23, 1915.

Application filed March 19, 1915. Serial No. 15,660.

To all whom it may concern:

Be it known that I, JASON C. STEARNS, a citizen of the United States, residing at Worcester, in the county of Worcester and 5 State of Massachusetts, have invented a new and useful Electrical Connecting-Socket, of which the following is a specification.

This invention relates to a socket member for use in making electrical connections. 10 The mounting of these sockets in automobile lamps especially has involved considerable trouble in the manufacture and assembling of the parts.

This invention is designed for the purpose 15 of producing a construction in which the usual metallic socket member can be so made that it can be applied to the lamp casing and brazed or otherwise treated by heat, or in any other desired way, and yet the connecting parts at the back of the socket can be inserted in it and permanently fixed to it 20 in a very simple way without spoiling the finish of the socket member and its surrounding parts, and without brazing or 25 other operation that requires the reheating of the parts.

Reference is to be had to the accompanying drawings, in which—

Figure 1 is a perspective view of a lamp 30 socket member constructed in accordance with this invention with the parts in a condition assumed in the art of being assembled; Fig. 2 is a similar view showing the device completed, and Fig. 3 is a sec- 35 tional view of a head light showing another way in which the invention can be used.

The invention is shown in Figs. 1 and 2 as applied to a cylindrical metallic socket member 10 adapted to hold an incandescent elec- 40 tric lamp 11 in a well known way. This socket member is formed with a longitudinal slot 12 extending in from the end and having at its inner end a transverse slot 13 at one side. On the other side of the slot 12 45 is a transverse notch 14 located a slight distance nearer the end of the member than is the slot 13. This forms a circumferential tongue 15 between the slot 13 and the end of the member and this tongue is preferably 50 provided with a rounded surface 16 at its outer side. This tongue is capable of being bent outwardly in a transverse direction, as shown in Fig. 1 and it is manufactured and supplied in that manner.

55 A plug or connecting element 17 is shown having a projection or pin 18 for connect-

ing it with the socket member. In assembling these two parts, the plug is introduced in such a manner that the pin 18 enters the slot 12, being guided in part by the surface 60 16 if desired and is then pushed in and turned into the notch 14. This having been accomplished the tongue 15 is bent down into the position shown in Fig. 2 and the pin 18 is thus permanently held in position and 65 the two parts 10 and 17 securely fixed together. In Fig. 3 the same construction is shown as applied to a lamp casing 20 and mirror 21. Here the socket member 10a is fixed to the casing and a plug 22 inserted 70 as described in connection with Figs. 1 and 2. This plug is connected with the lamp 11a in the usual manner. From this it will be seen that this union of the parts is effected in a very simple and expeditious manner 75 and without heating the parts in any way so that any surface finish with which the parts may have been supplied is left intact and there is no danger of injuring them.

Although I have said that the parts are 80 permanently united, it will be clear that if it is desired to disconnect them at any time, that can be done simply by bending back the tongue 15 and that even after several replacements, the parts will not be injured and 85 will be fully effective for the purpose intended.

Although I have illustrated and described only two embodiments of the invention, I am aware of the fact that many other modifications can be made therein by any person skilled in the art without departing from the scope of the invention as expressed in the claims. Therefore, I do not wish to be limited to all the details herein shown and 90 described, but

What I do claim is:—

1. As an article of manufacture, an electrical connecting socket comprising a socket member having a notch therein and a tongue 100 normally closing the end of the notch and being capable of being bent out of registration with the notch, and a member entering and fitting the socket member and having a projection adapted to enter said notch when 105 the tongue is bent away from it.

2. As an article of manufacture, an electrical lamp socket comprising a cylindrical socket member having a notch therein and a tongue projecting toward the notch and 110 normally closing the end thereof, said tongue normally lying within the cylindrical sur-

face of the socket member but being capable of being bent transversely away from the notch so as to expose the notch, and a plug member entering the socket member and 5 having a pin projecting radially therefrom and adapted to be located in the notch when the tongue is bent into the cylindrical surface of the socket member.

3. As an article of manufacture, a cylindrical socket having a slot extending in longitudinally from one end and provided at 10 its end with a circumferential transverse slot on one end and with a transverse notch

on the other near the end, the transverse slot forming a circumferential tongue between 15 it and the end of said socket member, whereby said tongue can be bent away from the notch to open it and can be bent toward it to close its end.

In testimony whereof I have hereunto set 20 my hand, in the presence of two subscribing witnesses.

JASON C. STEARNS.
